UNITED STATES PATENT OFFICE.

PEDRO VILARDELL FORCADA, OF BARCELONA, SPAIN.

RADIATOR.

Application filed November 26, 1924, Serial No. 752,453, and in Spain January 31, 1924.

This invention relates to a radiator for explosion engines, particularly applicable to automobiles and air craft.

It is characterized by the feature that the members through which the water to be cooled passes are constituted by tubes coiled in the form of a helix and straight tubes that pass longitudinally therethrough.

One of the advantages of this radiator is that a portion of the water, to traverse the height of the former, has to travel over a long path, being thus greatly cooled.

Another of its advantages is that the radiator constructed in this manner is of light weight, stronger and less liable to be damaged than those known up to the present time, on account of the reduced number of welds which it comprises and to the fact that the tubes which constituted the radiator may have very strong walls.

Finally, another advantage is that the said radiator is of simple and consequently economical construction, and that any repair which it may be necessary to make to these radiators is in all cases easily carried out.

A form of construction of the radiator according to the invention is illustrated diagrammatically by way of example in the accompanying drawing in which:

Fig. 1 is a part of a radiator core member.

Fig. 2 is a form of construction of the radiator.

In Fig. 1 is shown the shape of one constituent member of the radiator, this member consisting of a tube 1, coiled in the form of a helix, the diameter of which may be varied, as may be the section and size of the tube, and the metal or alloy of which it is made.

Similarly, the above mentioned tube may be coiled so that the cross section of the member formed will be an ellipse, an oval, a polygon or any other suitable shape.

The following will also vary: the general

shape of the radiator, that of its frame or armature, the material from which it is constructed, and the manner in which the said members are attached to it, as well as the number of these members which enter into the construction of each radiator.

These constituent helical members are interlaced or intertwined by advancing one member into the adjacent member in the manner of a screw as will be seen on reference to Figure 2. Straight tubes 3 are then combined with the helical tubes by passing same longitudinally through the spaces formed within the helical tubes.

In Figure 2 the straight tubes are shown as passing through the lenticular spaces formed by the interlacing of adjacent helical tubes. By such a construction the radiator is strengthened and a greater cooling surface results therefrom.

What I claim is:—

1. A radiator core for use with the cooling system of automobile engines and the like, including a series of substantially parallel interlaced helical tubes in combination with straight tubes passing longitudinally through the lenticular spaces formed by the interlaced helical tubes and lying contiguous to said helical tubes, all of said tubes being adapted to convey water, and the straight tubes functioning to strengthen the interlaced helical tubes.

2. In a radiator core for the cooling system of automobile engines and the like, a series of substantially parallel interlaced helical tubes in combination with straight tubes passing longitudinally through the lenticular spaces formed by adjacent helical tubes, each of said straight tubes engaging a plurality of the convolutions of said helical tubes to strengthen the latter, and all of said tubes being adapted to convey the cooling liquid.

In testimony whereof I have signed my name to this specification.

PEDRO VILARDELL FORCADA.
